UNITED STATES PATENT OFFICE.

JAHN KEPKO, OF NATRONA, PENNSYLVANIA, ASSIGNOR OF ONE-HALF TO JOHN KOVAC, OF NATRONA, PENNSYLVANIA.

EXPANSIBLE BED.

1,101,288.

Specification of Letters Patent. Patented June 23, 1914.

Application filed April 15, 1914. Serial No. 831,955.

To all whom it may concern:

Be it known that I, JAHN KEPKO, a subject of the Emperor of Austria-Hungary, residing at Natrona, in the county of Allegheny and State of Pennsylvania, have invented certain new and useful Improvements in Expansible Beds, of which the following is a specification.

This invention relates to certain new and useful improvements in expansible beds.

The primary object of this invention is the provision of a double bed adapted to form a triple-sized bed, the separate parts of which may be readily disassembled and re-arranged.

A further object is to provide two separate bed sections having telescoping members for forming a third similar section positioned therebetween and adaptable as a unitary structure when all taken together.

A still further object is to provide two bed members which are readily disassembled and are so positionable at desired distances apart to form an intermediately-positioned bed of similar dimensions.

With these and other objects in view as will appear as the nature of the invention is better understood, the same consists in the novel combination and arrangement of parts hereinafter fully described, illustrated in the accompanying drawings, and pointed out in the appended claims.

In the drawings forming a part of this application and wherein like designating numerals refer to corresponding parts throughout the several views:—Figure 1 is a top plan view of the device fully extended and illustrating the three sets of bed slats in dotted lines. Fig. 2 is a longitudinal sectional view taken upon line II—II of Fig. 1, looking in the direction of the arrows and showing one of the main bed sections in dotted lines, as shifted in contact with the co-operating sections. Fig. 3 is a detail perspective view of a corner portion of one of the main bed sections showing the telescopic connecting means partially broken away. Fig. 4 is a detail perspective view of an end portion of one of the rails of the bed showing in dotted lines the ends of the adjacent slats engaging thereon, and, Fig. 5 is a vertical sectional view upon line V—V, of Fig. 1.

Referring more in detail to the drawings, the main bed sections 10 and 11 are illus-

trated, being substantially identical in form and each provided with similar opposite ends 12 corresponding to the head and the foot of each of said beds. Side rails 13 are secured to the bed ends 12 by means of the sockets 14 carried by the ends and pins 15 carried by said side rails for engaging within the said sockets in substantially the usual manner. The side rails 13 of each of the beds 10 and 11 are provided with upwardly projecting ribs 16 at the outer marginal edges thereof and similar ribs 17 centrally projecting upwardly from the adjacent ones of said side rails of the beds. One of said beds and here illustrated as the bed 10, has the rectangular bars 18 transversely secured adjacent the end 12 thereof and provided with outer portions 19 extending through slots 30 in the inwardly-projecting arms 23 of said ends, the said bar portions being substantially U-shaped in cross-section and forming valleys for the sliding reception of the connecting rods 20 and their enlarged heads 21 positioned therein. The opposite ends of said rods 20 project through slots 22 in the inwardly-projecting arms 23 of the ends 12 of the bed 11 and have their outer ends provided with heads 24 secured within slots 25 in the outer ones of said arms 23 of the ends of said bed 11. The bars 18 are provided with terminal heads 31 secured to the outer arms 23 of the ends 12 of the bed 10.

Each of the beds being formed as herein described, it will be seen that the side rails 13 thereof are readily assembled with the bed ends 12 by means of the inter-engagement of the sockets 14 and the pin 15, and in which position the ends of said rails rest upon the ledges 26 of the arms 23 inwardly projecting from said ends. To disassemble the beds, it is only necessary to remove the side rails from the end members and the entire structure will then consist of the two foot and head members connected together by the telescoping bars while the four rails will be separate therefrom.

With the rods 20 positioned in the valleys 19 of the bars 18, it will be seen that the plates 27 covering said valleys at the free ends thereof prevents said rods 20 from being removed therefrom while said free ends of the bars 18 are adapted to pass through the slots 22 of the bed member 12 when the bars 18 and the two adjacent side rails of

the two beds are brought in contact with each other, as partially illustrated in dotted lines in Fig. 2.

With the beds 10 and 11 completely separated to the limit of their movement, slats 28 are adapted to be positioned upon the adjacent inner side rails 13 with their opposite ends engaging the rods 17 as illustrated in dotted lines in Fig. 1 and thereby forming a complete bed between the beds 10 and 11 while similar slats 29 are positioned upon the beds 10 and 11 between the ribs 16 and 17 of the opposite side rails thereof. It will thus be seen that the two separate bed members 10 and 11 are adapted for positioning in contact with each other or separated apart sufficiently to provide an intervening bed of similar dimensions and by which construction, the triple-sized bed may be so folded during the day-time as to take up only the room of the double bed formation.

While the forms of the invention herein shown and described are what are believed to be preferred embodiments thereof, it is nevertheless to be understood that various forms and modifications may be resorted to which come within the spirit and scope of the invention as claimed.

What I claim as new is:—

- 30 1. A device of the class described, comprising two separate bed members having side rails provided with alining perforations through the adjacent sides thereof, telescoping bars projecting through said
- 35 perforations and having their opposite outer ends rigidly secured to the outer side rails of said beds, upwardly-projecting ribs carried by each of the side rails of said beds, and slats adapted for seating upon said side
- 40 rails positioned between the said ribs thereof.
- 45 2. A device of the class described, comprising two similar bed members having ends and connecting side rails, inwardly-projecting arms carried by said ends in removable engagement with said rails, said beds adapted for positioning side by side and having the adjacent arms thereof provided with alining perforations there-through, bars secured to the outer arms of
- 50 one of said beds and extending through the slots of the inner arms of the same bed and provided with longitudinal valleys therein, rods secured to the outer arms of the other one of said beds and extending through the
- 55 slots of the adjacent arms of the same bed and having enlarged ends slidably positioned within the valleys of said bars, retaining plates secured over said valleys and

the said rods positioned therein, the said rods adapted for telescoping within said bars upon the contacting of the adjacent inner side rails of said beds.

3. A device of the class described, comprising two similar bed members having ends and connecting side rails, inwardly-projecting arms carried by said ends in removable engagement with said rails, said beds adapted for positioning side by side and having the adjacent arms thereof provided with alining perforations there-through, bars secured to the outer arms of one of said beds and extending through the slots of the inner arms of the same bed and provided with longitudinal valleys therein, rods secured to the outer arms of the other one of said beds and extending through the slots of the adjacent arms of the same bed and having enlarged ends slidably positioned within the valleys of said bars, retaining plates secured over said valleys and the said rods positioned therein, the said rods adapted for telescoping within said bars upon the contacting of the adjacent inner side rails of said beds, upwardly-projecting marginal ribs carried by the outer ones of said side rails, upwardly-projecting central longitudinal ribs carried by the inner ones of said side rails, and supporting slats positioned between the adjacent ones of said rails and with their opposite ends positioned between the adjacent ones of said ribs.

4. A device of the class described, comprising two separate bed members having side rails provided with alining perforations through the adjacent sides thereof, telescoping bars projecting through said perforations and having their opposite outer ends rigidly secured to the outer side rails of said beds, upwardly-projecting ribs carried by each of the side rails of said beds, slats adapted for seating upon said side rails positioned between the said ribs thereof, inwardly-projecting arms carried by said ends and provided with sockets therein, pins upon the opposite ends of said side rails and adapted for seating within said sockets, ledges inwardly-projecting from the lower portion of said arms beneath the adjacent ends of said side rails and pin.

In testimony whereof I affix my signature in presence of two witnesses.

JAHN KEPKO.
